AWNNG WINDOW CONSTRUCTION

Elmer A. Westman, Fenton, Mich., assignor to Industrial Machine Tool Company, Inc., Fenton, Mich., a corporation of Michigan

Application September 11, 1953, Serial No. 379,554

4 Claims. (Cl. 189—67)

This invention relates to an improved window assembly. It relates particularly to that type of window assembly commonly termed an awning window wherein one or more swinging sash are pivoted upon horizontal pivots within a frame for swinging movement outwardly and for raising and lowering of the pivotal mounting as the sash swing.

Such window structures are coming into wide use because of their convenience in providing ventilation while at the same time preventing the entrance of rain though the window may be partly open.

An object of this invention is to provide such a window assembly wherein the operating mechanism is so constructed as to facilitate opening and closing of the sash and wherein the construction is such that the friction of such opening and closing movement is reduced to a minimum and the sash may be easily swung to and from the open and closed positions.

Another object is the provision of a window assembly of the character described wherein the various parts of the operating mechanism are so designed and arranged as to produce a compact assembly of a finished character with a minimum of exposure of fastening devices on the outside of the window frame.

An important feature of the invention is the provision of complementary brackets which are channel-shaped in cross section and which are mounted within channel-shaped jamb members and which brackets serve as guides to support linearly slideable bars that form a part of the operating mechanism for swinging the sash. An advantage is that the brackets are so constructed and the slideable bars are so formed that the bars travel through the brackets with a minimum of friction and the operation of the mechanism is thereby facilitated.

The brackets serve not only to support the slideable bars for up and down movement but they also pivotally support the fulcrum links which links are pivoted at their outer ends to the sash to support the sash for swinging movement.

The brackets are so designed as to seat within the channel-shaped jamb members though such jamb members may vary as to the accuracy of their cross sectional channel formation. The bottom corners of the brackets are provided with projecting seating ridges which engage snugly within the corners of the channel jamb to properly support the bracket and the bottom of the bracket and one side wall thereof are supported spaced from the bottom of the adjacent side wall of the channel jamb.

Other objects, advantages and meritorious features will more fully appear from the following specification, claims and accompanying drawings wherein:

Fig. 1 is a perspective of a window assembly embodying the invention;

Fig. 2 is an elevation partly broken away of the window assembly shown in Fig. 1;

Fig. 3 is a vertical sectional view through the window assembly shown in Fig. 2 showing the sash closed;

2

Fig. 4 is a cross sectional view taken on the line 4—4 of Fig. 3;

Fig. 5 is a vertical sectional view taken on the same line as Fig. 3 but showing the swinging sash at an open position;

Fig. 6 is a cross sectional view taken through a window assembly on the line 6—6 of Fig. 3;

Fig. 7 is a perspective of a fragment of a lower sash and operating mechanism therefor associated with the supporting bracket.

Fig. 1 illustrates a window assembly comprising upper and lower sash indicated as U and L respectively, disposed between the jamb portions 10 of the window frame, a sill which is indicated as 12, and a header 14. The jambs are complementary and spaced apart by the header and the sill. The individual jamb portions and the header portion and the sill portion are all channel-shaped in cross section, as shown particularly in Figs. 3, 5 and 6. The channels open outwardly, i. e. outwardly of the building. As shown in Figs. 4 and 6 particularly, the outer side wall of each channel section has a height greater than that of the inner side wall. A flange 16 extends outwardly from the outer side wall. Flange 18 extends inwardly of the window opening from the inner side wall. The flange 18 is disposed substantially midway within the plane of the window.

The sash are here shown as provided with metal frames of conventional construction and having face plate portions 20 which cover the jamb channel openings when the sash are closed. These face plates 20 also overlap the flanges 16, as shown in Fig. 6. The header 14 is shown as provided with an outer weather protective inner flange 22 secured thereto to overhang the top rail of the upper sash, as shown in Figs. 3 and 5.

The window assembly illustrated shows two swinging sash, but obviously any number of swinging sash desired might be provided, from one to a large plurality. The sash are disposed between the jambs as is common in this type of window and each sash is supported for swinging movement by a pair of complementary individual adjustable fulcrum links 24. The two links of the pair of positioned on opposite sides of the sash and each is pivoted at one end to the sash, as at 26, as shown particularly in Figs. 5 and 7.

Each of said links is pivoted at its opposite end at 28 to a bracket element hereinafter described. The link may be adjusted in any desired fashion, as for example, as shown in my copending application, Serial No. 218,031 filed March 28, 1951, which became Patent No. 2,688,779 on September 14, 1954, the link is adapted to fold alongside the sash within the channel of the jamb member when the sash is closed, all as shown in Figs. 2, 3 and 6.

An important feature of this invention is the bracket element to which the stationary end of the link is pivoted at 28. This bracket element is indicated as 30 and it is channel-shaped in cross section corresponding generally to the channel shape of the jamb member within which it is mounted.

Specifically, each bracket element has a bottom portion 32, on outer side wall portion 34, and an inner side wall portion 36. The bracket element is of a size to be snugly received within a channel of the jamb member. The bottom of the bracket is supported spaced from the bottom of the channel jamb by a pair of projecting corner ribs 38 and 40. Such are shown with particular clarity in Fig. 4. The rib 40 is so shaped as to seat within the adjacent corner of the channel jamb and space the side wall 36 of the bracket from the adjacent side wall of the jamb channel and space the bottom wall 32 of the bracket from the bottom wall of the jamb channel.

The bracket is shown as held in place by a screw 42 extending through the side wall 34 of the bracket and the

adjacent side wall of the jamb channel. The brackets are of relatively short length, as shown in Figs. 5 and 7. The brackets are complementary and one pair is disposed in proximity to the top of the window frame and the opposite pair in proximity to the bottom of the window frame. In Figs. 2, 3 and 5, the two adjacent brackets are shown at the bottom so as to provide greater length of support for the slide bars 44.

These brackets serve two functions. They serve to support the slide bars and the operating mechanism for slidable movement. They also serve as a support for the inner ends of the fulcrum links 24.

Inasmuch as the brackets are provided with ribs 36 and 40 hereinabove discussed, such brackets are adapted to seat snugly in the corners of the jamb channels regardless of slight malformations of such channels. Furthermore, the inner wall 36 of each bracket is disposed spaced from the adjacent inner wall of the jamb channel and provides ample clearance for the head of the flange 28 which secures the inner end of the fulcrum link 24 to such wall 36.

The slide bars 44 form a part of the operating mechanism and are slidably supported within the brackets as shown particularly in Figs. 4 and 6. Each slide bar 44 is cut away along one side providing a groove or a channel therein as shown at 46 and is provided with a groove 48 along each edge which groove 48 extends linearly of the slide bar, all as shown particularly in Figs. 4 and 6. Grooving the slide bar as described reduces its frictional contact with the inner face and the bottom of the bracket 30 so that it slides thereover readily. Each slide bar is held toward the bottom of the bracket channel by a guide element 50 projecting inwardly of the side wall 34 of the bracket and is held toward the side wall 32 by a guide element 52 projecting inwardly from the bottom of the bracket, as shown in Figs. 4 and 6. The brackets hold the slide bars from contacting throughout their length the interior of the channel jamb elements and facilitate the sliding movement of such bars. Each sash has a bracket arm 56 formed integrally with its top rail and the outer end of such arm is pivotally coupled with the slide bar by pivot pin 58.

Operating linkage is provided in the form of a crank 60 mounted on the shaft 52 which shaft is provided with a worm 64 which meshes with the gear segment on the end of the arm 68. This arm is pivoted at 70 within a housing 72 which housing is secured by rivets or the like 74 to the window frame. The outer end of the arm 68 is coupled by a link 76 with one arm 78 of a toggle mechanism.

The arm 78 is fixed to a rotatably supported shaft 80. Opposite ends of this shaft are journaled upon the jamb members because the shaft connects the two toggle mechanisms together, one for each jamb element, so that when the crank 60 is rotated the operating mechanism shown in Figs. 3 and 5 is actuated to rotate the shaft and lift the slide bars. The other link in the toggle is indicated as 82 and it extends from the link 78 to pivot 58 which connects the crank arm 56 at the top of the lower sash with the slide bar 44. It will be understood that complementary sets of operating mechanism are provided within each jamb and linked together through the shaft 80.

The employment of the brackets described above provides not only a pivotal support for the fulcrum links 24 but a guide for the slide bars 44 and the brackets support the slide bars for easy guided slidable movement and afford a good pivotal support for the swinging windows; they also facilitate the assembly of the sash and operating mechanism within the jamb members.

Though no part of this invention, the flange 18 of the inner side wall of the jamb channel is provided with gaskets 90, one of which is adapted to form a tight seal with a swinging sash and the other of which is adapted to form a tight seal with a storm sash when the same is placed in the window.

What I claim is:

1. In a window assembly, a frame having complementary jambs channel-shaped in cross section, complementary brackets channel-shaped in cross section correspondingly mounted one within each jamb and seated against opposite side walls of the jamb channels at the bottom thereof, said jamb channels and bracket channels being open outwardly, a swinging sash disposed between the jambs and having flanges adapted to close over the open sides of the channel frames, complementary fulcrum links upon opposite sides of the sash each pivoted to the sash at one end of the link and pivoted at the opposite end of the link to the inner side of the inner side wall of the adjacent bracket to fold within said channel bracket, a sash operator including a slide bar disposed within each jamb and coupled with the sash to swing the sash, each slide bar supported within the channel bracket of the jamb and held spaced from the side walls of the jamb channels for slidable movement over the outer side wall of the bracket, the outer side wall of each bracket provided with a guide rib adapted to engage the edge of the slide bar and the bottom of each bracket provided with a guide rib adapted to engage the side of the slide bar in its slidable movement through the bracket.

2. A window assembly as defined in claim numbered 1 characterized in that the bottom corners of the channel-shaped brackets are provided with downwardly projecting corner ribs adapted to seat within the interior corners of the channel jambs spacing the bottom of each bracket from the bottom of the jamb.

3. A window assembly as defined in claim numbered 1 characterized in that the bottom corners of the brackets are provided with downwardly projecting ribs adapted to seat within the interior corners of the jambs spacing the bottom of each bracket from the bottom of the jamb, that rib on the inner bottom corner of the bracket projecting laterally beyond the inner side wall of the bracket, spacing such side wall of each bracket from the inner side wall of the jamb.

4. In a window assembly, a frame having complementary jambs channel-shaped in cross section, two pairs of complementary brackets channel-shaped in cross section mounted within the two jambs, one pair in proximity to the tops of the jambs and the other pair in proximity to the bottoms of the jambs, a swinging sash for each pair of brackets disposed between the jambs, a pair of complementary fulcrum links for each sash disposed on opposite sides of the sash and each link pivoted at one end thereof to the sash and pivoted at the opposite end thereof to the inner side wall of the adjacent channel-shaped bracket and on the inner side of said wall, a sash operator including a slide bar disposed within each jamb and coupled with the adjacent sides of the two swinging sash, each slide bar disposed within the upper and lower channel brackets of its jamb adjacent to the outer side wall of the bracket for lengthwise slidable movement therethrough in spaced relation from the side walls of the jamb channels, said outer side wall of each bracket provided on its inside with a rib engaging the edge of the slide bar, the bottom of the bracket provided with a guide rib engaging the side of the slide bar to guide the slide bar in its sliding movement over the outer side wall of the bracket, each slide bar being grooved linearly along that side which is opposed to the outer side wall of the bracket and being grooved along that edge which is opposed to the bottom of the bracket.
